**INTERRUPTER FOR ROTARY OFFSET
PRINTING MACHINE**

Luis Mestre, New York, N. Y., assignor to Lewfor Development Corporation, New York, N. Y., a corporation of New York

Application September 2, 1953, Serial No. 378,035

14 Claims. (Cl. 101—144)

The present invention relates to offset printing machines and the principal object of the invention is to provide a machine of the type specified embodying novel and advantageous features of construction and capable of producing novel and advantageous results.

Machines of this character heretofore in use have comprised a plate cylinder, a blanket cylinder, an impression cylinder, a delivery cylinder, dampening means for the plate cylinder and inking means for the plate cylinder.

Another object of the invention is to provide novel and advantageous apparatus of the class specified, wherein absence of a sheet at the receiving position for the impression cylinder will cause the blanket cylinder to be thrown out of position to cooperate with the impression cylinder and the plate cylinder, but not until a complete impression has been made on the last sheet passed through over the impression cylinder.

Another object of the invention is to provide novel and advantageous apparatus of the class specified wherein the first impression after restoration of operative relation between a displaced blanket cylinder and the plate and impression cylinders will be complete.

Another object of the invention is to provide novel and advantageous apparatus of the class specified whereby absence of a sheet at the receiving position for the impression cylinder will set mechanism whereby upon completion of an impression on a sheet on said impression cylinder, the blanket cylinder will be moved out of operative relation with the plate cylinder and the impression cylinder.

Another object of the invention is to provide novel and advantageous apparatus of the class specified whereby absence of a sheet at the receiving position for the impression cylinder will set mechanism whereby upon completion of an impression on a sheet on said impression cylinder, the blanket cylinder will be moved out of operative relation with the plate cylinder and the impression cylinder and the ink supply to the plate cylinder will be stopped.

Another object of the invention is to provide novel and advantageous apparatus of the class specified whereby absence of a sheet at the receiving position for the impression cylinder will set mechanism whereby upon completion of an impression on a sheet on said impression cylinder, the blanket cylinder will be moved out of operative relation with the plate cylinder and the impression cylinder subject to manual restoration.

Another object of the invention is to provide novel and advantageous apparatus of the class specified wherein with the blanket cylinder out of operative position relative to the plate and impression cylinders, manual operation of a handle in one direction will displace the impression cylinder from operative position, the blanket cylinder to operative position and lock said handle against complete return movement, and automatic return movement of said handle will act first to return said handle to a locking position and set into operation means for unlocking the handle and restoring the impression cylinder to its effective position to receive a sheet of paper.

2

Another object of the invention is to provide a machine of the type specified embodying novel and advantageous means for gaging and aligning sheets of material such, for example, as papers for engagement by grippers on the impression cylinder.

Another object of the invention is to provide a machine of the type specified embodying novel and advantageous means for operating the ratchet wheels on the shafts of water fountain rollers and ink fountain rollers.

Another object of the invention is to provide a machine of the type specified embodying novel and advantageous means operated by a single manual control member to supply water and ink to the plate roller.

Another object of the invention is to provide a machine of the type specified embodying novel and advantageous means comprising a manually operable handle which in one position causes both water and ink to be supplied to the plate roller, in a second position causes water only to be supplied to the plate cylinder and in a third position causes the supply of both water and ink to be cut off.

Another object of the invention is to provide a machine of the type specified embodying novel and advantageous means for delivery of sheets from the impression cylinder with the optimum condition of light contact with the printed surface.

Another object of the invention is to provide a machine of the type specified embodying novel and advantageous means for stopping the supply of ink to the plate cylinder and separating the blanket cylinder from the plate cylinder and means for overcoming the stoppage of supply of ink to get a sufficient supply of ink on the plate cylinder preparatory to applying the matter inked thereon to the blanket cylinder.

Another object of the invention is to provide a machine of the type specified embodying means for shifting the impression cylinder from the blanket cylinder to permit a sufficient application to the blanket cylinder of the ink pattern on the plate cylinder.

Another object of the invention is to provide a machine of the type specified embodying novel and advantageous means comprising a detachable inking unit having only one operative connection with the main machine, which requires definite disconnection, other operative connections being broken merely by removal of the inking unit and reestablished by reinsertion of the inking unit.

Other objects are to provide machines of the type specified embodying novel and advantageous means for manual control for shifting certain cylinders and feeler-controlled means for the same purpose depending upon the presence or absence of sheets at the entrance of the machine.

Further objects, features and advantages will appear upon consideration of the following detailed description and of the drawings, in which:

Fig. 1 is a view in elevation of the front or operator's side of the machine;

Fig. 2 is a top plan view of the machine on a much larger scale than Fig. 1 and broken away longitudinally to narrow the figure;

Fig. 3 is a view on a larger scale of the upper part of the mechanism illustrated in Fig. 1;

Fig. 4 is a view on a larger scale of the lower part of the mechanism illustrated in Fig. 1;

Fig. 4a is a section taken along line 4a—4a of Fig. 4;

Fig. 5 is a vertical section of the upper part of the machine taken just inside the front plate of the frame;

Fig. 6 is a vertical section of the lower part of the machine taken just inside the front plate of the frame;

Fig. 7 is a vertical section of the part of the machine illustrated in Fig. 6, taken along line 7—7 of Fig. 2, the impression cylinder being in position for means carried thereby to grasp the leading edge of a sheet of paper fed thereto;

Fig. 8 is a sectional view showing the same parts as Fig. 7 but with the impression cylinder in position for release of the leading edge of a sheet of paper thereon and with the rotary-delivery device in position for its gripper means to grasp the leading edge of a sheet of paper as it is released from the impression cylinder;

Fig. 9 is a sectional view taken along the line 9—9 of Fig. 7;

Fig. 10 is a fragmentary top plan view illustrating the part of the machine of which Fig. 9 is a vertical transverse section;

Fig. 11 is a fragmentary view illustrating a sheet of paper in stopped position and with grippers on the impression cylinder about to close on the leading edge of the sheet;

Fig. 12 is a view similar to Fig. 11 but showing the gripper fingers closed to grasp the sheet;

Fig. 13 is a view similar to Figs. 11 and 12 but showing the impression cylinder with its gripper fingers open just after release of the leading end of a sheet;

Fig. 14 is a fragmentary view illustrating the gripping of the leading edge of a sheet by the delivery device as it is released by the gripper fingers of the impression cylinder;

Fig. 15 is a sectional view taken along line 15—15 of Fig. 7;

Fig. 16 is a fragmentary rear elevation of adjustable eccentric bearing means for the rear end of the shaft about which the impression cylinder rotates, partially broken away to show underlying structure;

Fig. 17 is a section on the line 17—17 of Fig. 16;

Fig. 18 is a fragmentary view similar to Fig. 16 but with parts in different positions;

Fig. 19 is a fragmentary view illustrating the position of parts at the front end of the impression cylinder when the cylinder is in eccentric position;

Fig. 20 is a section taken along line 20—20 of Fig. 19;

Fig. 21 is a section taken along line 21—21 of Fig. 20;

Fig. 22 is a section taken along line 22—22 of Fig. 20;

Fig. 23 is a fragmentary front elevation with paper sheets passing through the machine, limits of movement of certain parts in one direction being indicated in full lines and limits of movement in an opposite direction being indicated in dot-and-dash lines;

Fig. 24 is a section on line 24—24 of Fig. 23;

Fig. 25 is a section taken on line 25—25 of Fig. 24;

Fig. 26 is a front elevation of part of the mechanism shown in Fig. 3 with the parts in position for supply of water but no supply of ink;

Fig. 27 is a view similar to Fig. 26 but with the parts positioned for no supply of water and no supply of ink;

Fig. 28 is a sectional view illustrating the form rollers and associated inking mechanism;

Fig. 29 is a view of the inking mechanism as seen from line 30—30 of Fig. 28;

Fig. 30 is a view illustrating the mechanism of Fig. 29 as viewed from the left, certain parts being broken away;

Fig. 31 is a section taken on line 31—31 of Fig. 3;

Fig. 32 is a section taken on line 32—32 of Fig. 31;

Fig. 33 is a section taken on line 33—33 of Fig. 31;

Fig. 34 is a fragmentary vertical section through the axis of the roller in the water trough;

Fig. 35 is a view of the apparatus of Fig. 34 as seen from line 35—35 of Fig. 34;

Fig. 36 is a view in elevation illustrating the inking unit as withdrawn from the part of machine by which it is operated;

Fig. 37 is a sectional view illustrating the means for holding inking unit in position on the machine frame while the holding screws are turned to holding position or are turned in the opposite direction to release the unit; and

Fig. 38 is a section of the upper end of a link detachably connected to the means for operating the inking unit.

Referring to the drawings, the frame of the machine comprises front and rear frame members or plates 40 and

41 respectively, connected by means comprising a vertical cross piece 42 at the entrance end of the machine and a bottom cross piece 43 (Fig. 7). As illustrated in Fig. 1 the machine is mounted on a table 44 having a top 45 and legs 46.

Each sheet of paper 50 is picked from a pile or stack (not shown) and advanced to the offset printing machine by suitable feeding mechanism 51 here illustrated as comprising at its delivery end sheet supporting belts 52 inclined rearwardly from the front or operation side of the machine and cooperating with an overhead plate 53 and balls 54 held in openings in said plate 53 to press the rear edge of each sheet against a vertical aligning plate 55. Said belts pass around a correspondingly inclined roller 56 at the delivery end of the feeding mechanism 51.

Sheet stopping or gaging means

From the belts 52 a frictionally fed sheet 50 passes over a lower plate 57 and beneath an upper plate 58 to a position where it is stopped by engagement of its leading edge with substantially vertical fingers or teeth 59 of a comb 60 of a gage or stop 61. The lower ends of said teeth 59 are normally housed in slots 62 (Fig. 8) in a part of the plate 58 extending beyond the edge of plate 57, but at this time said teeth project below the lower face of plate 58 into the path of each sheet 50. Said stop 61 has a flat top 63 adjustably mounted on the top of a rockshaft 64 and provided at its forward edge with said fingers 59 which project downwardly at substantially right angles thereto. Said fingers 59 occupy alternate slots 62 in plate 58 leaving the remaining slots 62 free for the passage of spring gripper fingers 65 carried by an impression cylinder 66 having ends 66a. As shown in Fig. 9, fingers 59 are separated by high arched openings to accommodate gripper fingers 65.

Fixed to said impression cylinder 66 is a cam 67 having an outer edge in the shape of a circle except for a low part 68 (Fig. 5). Said cam 67 engages a follower 69 on an arm 70 adjustable around rockshaft 64 and holds the fingers 59 of said stop 61 in raised position after a sheet 50 has been picked up by impression cylinder 66 and holds said stop raised until another sheet approaches the position for engagement thereof by gripper fingers 65 of said impression cylinder 66. Said follower 69 is pressed against cam 67 by a spring 70a connecting an arm 70b on rockshaft 64 with a fixed pin 70c (Fig. 3).

A feature of the invention relates to novel and advantageous means for adjustably mounting the gage or stop 61 on said rockshaft 64, which means comprises a pivot 50 in the form of a screw 71 passing through an opening in top 63 of said stop 61 substantially midway between the ends thereof and threaded into said rockshaft 64 (Fig. 10a). The rear end of said stop 61 is urged forwardly by a helical compression spring 72 having one end mounted in a bore 73 in said shaft and the other end in engagement with the rear or inner face of said comb 60. Obviously the forward pressure of spring 72 on the rear end of comb 60 will urge the forward end of comb 60 and stop 61 rearwardly about the pivot 71 (Figs. 9, 10 and 10a).

The actual adjustment of alignment of stop 61 is effected by means of a nut 74 threaded on rockshaft 64 and having a tapered or conical end engaging a finger 75 projecting from the forward end of said comb 60 in an inclined direction for engagement by the tapered end of said nut 74. By screwing said nut 74 rearwardly the front end of said stop 61 will be moved forwardly in the direction of travel of the sheets and the other end of said stop will be swung rearwardly about said pivot 71 and against resistance of said spring 72. By movement of nut 74 in the proper direction the comb 60 may be adjusted to provide proper alignment for the leading edges of sheets 50 as the sheets are fed to the impression cylinder 66.

Another feature of the invention relates to regulation of the movement of stop 61 about the axis of rockshaft

64 by adjusting the position of arm 70 around said rock-shaft, thereby regulating the range of movement of stop 61 and of the ends of stop fingers or teeth 59. As illustrated in Figs. 9a and 9b, arm 70 is flat and has at its inner end a hub 76 mounted on rockshaft 64 and fixed to a collar 77 rotatably mounted on the same rockshaft. At one side of hub 76 is a projection 78 having at its lower edge an ear 79 at a right angle thereto and having a screw-threaded opening therein.

Adjacent to hub 76 is a hub 80 mounted on rockshaft 64 and secured to a collar 81 which is fixed on rockshaft 64. Said hub 80 has an ear 82 projecting laterally over ear 79 and having an opening therethrough to receive a bolt or screw 83. Said screw 83 is inserted through the opening in ear 82 and a helical spring 84, and is screwed into the screw-threaded opening in ear 79. Said helical spring 84 urges ears 79 and 82 apart to the distance permitted by screw 83. The adjustment of the arm 70 with reference to rockshaft 64 may be varied within suitable limits of adjustment by turning screw 83 to the required position.

Impression cylinder and sheet-gripping device

The surface of said impression cylinder 66 is cylindrical except for a longitudinal channel or trough 90 to accommodate said gripper flanges 65 and shaft 91 on which they are mounted. Said shaft 91 is mounted in the ends 66a of impression cylinder 66. As shown on Fig. 9, fingers 65 are spaced to pass through slots 92 in a cover 93 for said channel 90, other slots 92 receiving the fingers 59 of stop 61 at the time the stop is lowered.

Fixed on the rear end of said shaft 91 (Figs. 11 and 12) is a tumbler or block 94 having in its rear face a cam groove 95 in the form of a straight central part and flared ends. Pivot on a screw pivot 96 on block 94 at its inner face and at the end remote from fingers 65, is a link 97 curved around a hub 98 and connected at its other end by a pivot 98a to one end of a lever 99 mounted between its ends on a pivot 100 projecting from the adjacent end of the impression cylinder 66 and at the other end to the end of a link 101.

Said link 101 comprises an angle 102 having a flange connected by a pivot 103 to lever 99, and a second flange perpendicular to the first from which projects a rod 104 which is slidable in a member 105 on a pivot or screw 106 in the rear end of 66a of said impression cylinder 66. Interposed between said angle 102 and member 105 is a helical compression spring 107 held in compressed condition by one or more nuts 108 threaded on said rod 104. The linkage comprises link 97, lever 99, rod 104 and spring 107 which act to complete the movement of block 94 when carried past center.

The action of the gripper fingers 65 near the position where they receive the sheets 50 from the feeding mechanism 51 is controlled by a pin 109 fixed in the rear frame member 41 of the machine, farther from the axis of the cylinder 66 than shaft 91, and the action of said gripper finger 65 near the discharge position is controlled by a pin 111 (Fig. 9) also fixed in said back frame member 41 closer to the axis of cylinder 66 than the shaft 91.

As the shaft 91 approaches the sheet gripping position the gripper fingers 65 project forwardly and the corresponding flared end of cam groove 95 of block 94 is in a position for pin 109 to enter the same and by engagement with the outer inclined edge 95a of the groove to cause turning of shaft 91 in a clockwise direction to move gripper fingers 65 toward gripping positions. As the block 94 is carried past center, pin 109 is engaged by the opposite inclined edge 95b to control final movement of finger 65 to gripping position (Fig. 12).

As the shaft 91 approaches its lowermost position pin 111 will enter cam groove 95 at the end remote from fingers 65 and strike the inner inclined edge 95c to turn block 94 counter-clockwise until it moves past center and

is restrained by the opposite inclined edge 95d. Such rocking movement of tumbler or block 94 carries it to a position with fingers 65 in ineffective position and projecting forwardly.

5 In passing from the sheet receiving position of the impression cylinder 66 to the sheet discharge position each sheet is fed between the impression cylinder 66 and a blanket cylinder 112 on which the ink has been applied by a plate cylinder 113 (Fig. 5). The ink is applied to the plate cylinder by means of an inking unit and water is supplied by a water supply unit. The sheets 50 as they are released from the impression cylinder 66 are grasped by spring gripper fingers 114 of a rotary delivery device 115 (Fig. 14).

Power drive

The machine is driven by an electric motor 120 controlled by a switch 121 (Fig. 1). Said motor 120 is illustrated as suspended from the top 45 of table 44 on which the machine is mounted. A pulley 123 on the motor shaft at its rear end is connected by means such as a belt 124 with a pulley 125 on a shaft 126 mounted in the machine frame and another belt 127 connects another pulley 128 on shaft 126 with a pulley 129 on shaft 130 which is the drive shaft for the machine.

25 A pinion 131 (Fig. 5) on shaft 130 at the front of the machine meshes with and drives a gear 132 fixed to plate cylinder 113. Gear 132 meshes with gear 133 fixed to blanket cylinder 112. Gear 133 meshes with gear 134 fixed to impression cylinder 66. Gear 134 meshes with gear 135 fixed to rotary delivery device 115 (Fig. 6). Gear 135 meshes with a gear 136 on the shaft 137 of a roller 138 which cooperates with delivery device 115 to deposit sheets 50 with offset printing thereon in an inclined chute 139 (Fig. 7). Gear 134 of the impression cylinder 66 meshes with a pinion 142 fixed on a shaft 141 and a second pinion 144 fixed on said shaft 141 meshes with a gear 143 on a cam shaft 144. When the motor switch 121 is in off position the parts of the machine may be moved to different position by means of a hand wheel 40 150 (Fig. 1) fixed on drive shaft 130.

Rotary delivery device

Rotary delivery device 115 (Fig. 6) and gear 135 are fixed on a shaft 151 rotatably mounted in front and rear frame members or plates 40 and 41 respectively and the delivery device 115 comprises end circular disks 152 and intermediate disks 153 having aligned notches or openings 154, all of said disks 152 and 153 being fixed on said shaft 151 (Figs. 4 and 15). A shaft 155 is journaled in said end disks 152 and passes through said openings 154. Mounted on said shaft 155 are said spring gripper fingers 114. An arm 157 is fixed on shaft 155 adjacent to left hand disk 152 (Fig. 15) and is connected by a spring 158 to a pin 159 fixed to said left hand disk 152 (Fig. 6). Spring 158 urges said shaft 155 in a counter-clockwise direction to press gripper fingers 114 against the corresponding disks 153 to grip the leading edges of sheets 50 discharged from the impression cylinder 66. The shaft 155 is turned clockwise against the action of spring 158 by an arm 160 fixed on shaft 155 and having at its outer end a follower 161 engaging the edge of a cam 162 fixed to rear plate 41 (Figs. 6 and 15).

As indicated in Fig. 8 the gripper fingers 114 which pass between gripper fingers 65 of the impression cylinder 66 are about to grasp the leading edge of sheet 50 which is about to be released by gripper fingers 65. Then as the delivery device 115 advances the sheet between said disks 153 and said roller 138, the sheet is released by gripper fingers 114 and is deposited on said inclined chute or tray 139.

The plate cylinder 113 is mounted on a shaft 170 carried by the frame members 40 and 41 and when the machine is in use, a suitably prepared plate 171 is mounted on the surface of a cylinder with its ends held by suitable

means in an open longitudinal recess 172 in said cylinder (Fig. 5).

The blanket cylinder 112 (Fig. 24) is rotatable on a shaft 175 of which the ends are mounted eccentrically in cylindrical journal members 176 and connected thereto as by keys to prevent relative angular movement about the axis of said shaft. Said journal members 176 are mounted for turning movement in corresponding bearing member 177 fixed in said frames 40 and 41.

By turning the shaft 175 and journal members 176 in said bearing member 177 the blanket cylinder may be shifted transversely relative to the plate cylinder 113 and to the impression cylinder 66. Such adjustment of blanket cylinder 112 may be effected manually or automatically for purposes to be brought out hereinafter. As disclosed herein said journal members 176 are mounted in said bearing members 177 by ball bearings 178, thus facilitating adjustment of position of the blanket cylinder. When the machine is in use a blanket 179 (Fig. 5) of suitable material such as rubber is mounted on cylinder 112 and its ends are secured in longitudinal openings 180.

The impression cylinder 66 is mounted on a shaft 182 by ball bearings 183 interposed between the ends 66a of the cylinder and said shaft 182. At the side of the cylinder end at the front of the machine said shaft 182 is mounted eccentrically in a cylindrical journal member 185 and these two parts are held against relative turning as by means of a key. Said journal member 185 turns in a bearing member 186 fixed in said frame member 40 (Fig. 20) and serves to position the shaft 182 to support cylinder 66 at the desired level. Such positioning is disclosed in Figs. 19 through 22 and the corresponding part of the description.

At the back of the machine the shaft 182 passes through hub 98 fixed to the adjacent end of the cylinder (Fig. 17) and eccentrically into a cylindrical journal member 187. Said journal member 187 fits into a bearing member 188 fixed in an opening in rear frame member 41, and is provided with a flange 189 which is secured to frame member 41 at its outer face by suitable means such as screws 190.

A plate 191 fits over the said shaft 182 and is secured to said journal member 187 by suitable means such as screws 192. Outside of said plate 191 is a plate 193 having an opening 194 to fit over the outer end of shaft 182 which has parallel flats 195 thereon. Said plate 193 is held on the outer end of shaft 180 by a screw 196, extending into the end of shaft 182. Adjustment between shaft 182 and journal member 188 may be effected by means of a screw 197 passing through an arcuate slot 198 in plate 193 and threaded into plate 191. This adjustment comprises paralleling means for bringing the rear eccentric bearing into desired position relative to the shaft.

The supply of water and ink to the plate (Figs. 1 and 4) during operation of the machine is effected primarily by means actuated by cam shaft 144. Eccentrically mounted on a member such as a circular disk 210 at the front end of said shaft 144 is a pivot 211 in the form of a screw passing through one end of a link 212 and screwed into said member 210. Said link 212 extends upwardly and toward the delivery end of the machine and is connected by a pivot 213 to a member or lever 214 mounted on a pivot 215 substantially midway between its ends. Said pivot 213 is at the delivery side of pivot 215.

At the left end of lever 214 is a pivot 216 connected to an inking unit and at the right end of said lever is a pivot 217 connected to a water supply unit. In this connection it should be kept in mind that both water and ink must be supplied to the plate cylinder during normal operation of the machine. A line through pivots 216 and 217 passes below the center of pivot 215 and above pivot 213 which is to the left of pivot 215.

Said water supply or fountain unit (Figs. 34, 35) is actuated from said lever 214 by a link 219 connected at its lower end to said pivot 217 and at its upper end to a pivot 220 on a pawl-carrier 221 mounted on shaft 222 of a roll 223 dipping into a tray or fountain 224 receiving water from a container 225 (Fig. 1). A ratchet wheel 226 is fixed on shaft 222 and is operated (Fig. 35) by a pawl 227 on a pivot 228 on said pawl-carrier 221 and urged into engagement with said ratchet wheel 226 by a spring 229 wound on said pivot 228 and engaging a pin 230 projecting from said pawl 227. To the front of said ratchet wheel 226 is a shield device 231 in the form of a disk adjustable about the axis of shaft 222 and having a cam edge arranged to engage said pin 230 and lift the pawl 227 when its stroke exceeds the desired length.

Said shield device may be held in different positions by a detent in the form of a spring pressed bolt or plunger 232 mounted in a casing 233 fixed to frame member 40, and having an end adapted to fit between teeth 234 of said shield. A holding pawl 235 may be pivoted at 236 on the adjacent frame member and may for convenience be spring pressed against said ratchet wheel 226 by suitable means such as a leaf spring 237 with an end fixed on said casing 233. The position of said shield device 231 may be varied by means of an arm 238 fixed on said shield device 231.

Said roll 223 is rotated in a clockwise direction and supplies water from tray 224 to a second or ductor roll 240 on a shaft 241 mounted in arms 242 between the frame members 40 and 41 and fixed on a shaft 243. On said shaft 243 is fixed an arm 244 having at its outer end a cam follower 245 in position to be engaged by a cam surface or edge 246 on said pawl carrier 221 and to be swung against the action of a spring 246a (Fig. 35). The roll 240 is thus moved back and forth between roll 223 and a roll 247 on a shaft 248. Roll 247 is pivoted in arms 248a loosely mounted on shaft 243 and urged by springs 249 into contact with a molleton roll 250. Said roll 247 and shaft 248 are oscillated by a conventional device 251a (Fig. 2).

A gear 251 on shaft 248 meshes with a gear 252 (Fig. 5) rotatable on shaft 243 and meshing with gear 132 of the plate cylinder. These connections result in positive rotation of roll 247 and rotation of roll 250 by contact with roll 247. The roll 250 is thus given the same surface speed as the plate cylinder 113 to which it supplies water. Said roll 250 is rotatable on shaft 253 which has at its ends opposite flats 254 which enable it to be held without turning in slots in plates at front and back of the machine. The ends of said shaft 253 are located in openings 255 (Figs. 26, 27) of vertical slides 256 held down by springs 257 connecting their lower ends to the outer ends of fixed pins 258 projecting through openings 259 in said slides 256.

The supply of water to the plate cylinder 113 may be interrupted by moving said slides 256 upwardly thereby separating roll 250 from said plate cylinder 113. The upward movement of said slides may be effected by bent levers or bell cranks 260 mounted on pivots carried by fixed frame members. Each bell crank 260 has a generally horizontal arm 261 connected by a pivot 262 to the lower end of the corresponding slide 256 and a generally vertical operating arm 263 extending downwardly from pivot 262.

The means for actuating arms 263 also acts to control the inking means as will be brought out hereinafter. Gear 132 (Fig. 5) of the plate cylinder also meshes with a gear 264 rotatably mounted on a shaft 265 journaled in frame members 40 and 41 and through said gear 264 operates parts of the inking mechanism.

Said pivot 216 at the left end of lever 214 (Fig. 3) is connected to the lower end of a link 270 which is connected to a pawl carrier 271 by means of a pivot or pin 272. The inking unit is removable and to that end the

connection between link 270 and pawl carrier 271 is constructed for easy connection or separation. Said pivot 272 (Fig. 38) is slidably mounted in the outer end of a cylindrical housing 273 fixed at its inner end in an opening in link 270. A stem 274 of reduced cross section extends through a helical spring 275 to a knurled head 276 by which the pivot 272 may be drawn back into the cylinder. Said spring 275 is confined between a shoulder on the stem 274 and a shoulder at the opposite end of the housing 273.

After drawing back pivot 272 into the housing 273 the portion of the pawl carrier 271 provided with a pivot receiving opening may be placed at the inside of the link 270 and the pivot 272 may be projected through the opening in said pawl carrier 271 and into an opening in a member 277. Said member 277 is parallel to the link 270 at the pivot 272 and, at a suitable distance from the pivot, is offset so as to be against the link 270 and be secured thereto by one or more fastening devices such as screws 278.

The inking unit which is detachable from the main frame as shown in Figs. 36-38 comprises end frames 40a and 41a of which the bottom edges are positioned on correspondingly upwardly facing edges of the main frame members 40 and 41. To facilitate introduction and removal of the inking unit the frames 40a and 41a are provided at their outer surfaces with plates 280 fastened to the outer surface of the frames 40a and 41a by screws 285a. The front and rear frame members 40 and 41 are provided with outwardly projecting pins 282 to be received in slots 283 at the ends of said plates 280.

The frame members 40a and 41a are placed on the corresponding parts of the main frame members and are moved forwardly until the pins 282 are engaged by the ends of said slots 283. In this movement openings 284 are brought into alignment with spring pressed pins 285 which are drawn back to permit the plates 280 to engage the outer surfaces of the main frame members 40 and 41. When the inking unit is in place the pins 285 are advanced by springs 286 into said openings 284 and the frame of the inking unit is held in position on the main frame members 40 and 41, being further secured by screws 285a above said pins 285.

As shown in Fig. 37 each pin 285 has a flange 287 which is positioned to engage a shoulder 288 at the bottom of a bore in each of the frame members 40 and 41. Spring 286 on a reduced stem 290 in a housing 291 presses the pin 285 into the opening 284, the outer end of the spring being engaged by a plug 292 screwed into said housing. The movement of the pin 285 by the spring 286 is limited by a cap 293 screwed on the end of said stem 290 and engaging the outer end of said housing. A pin 289 of small cross section projects from said cap 293 into plug 292 at one side and may serve to hold pin 285 retracted when it is drawn out and turned slightly to position pin 289 against a solid part of the outer surface of plug 292. This feature is of substantial value in connection with removal or replacement of an inking unit.

A pawl 294 is mounted by means of a pivot 295 on said pawl carrier 271 and is urged against a ratchet wheel 296 (Fig. 33) by means of a spring 297 extending around said pivot and having an end engaging a pin 297a on said pawl 294. Actuation of the pawl carrier 271 by means of the link 270 will turn the ratchet wheel 296 in a counter-clockwise direction. Said ratchet wheel 296 is mounted on a shaft 298 and a roll 299 mounted on shaft 298 dips into an ink container or fountain 300 (Fig. 5). A ductor roll 301 is rotatably mounted in arms 302 fixed on a shaft 303. Also fixed on said shaft 303 is an arm 304 provided with a follower 305 extending through a hole 306 in the frame 40a and engaging a cam edge 307 (Fig. 33) on the pawl carrier 271 which during the back and forth movement of the pawl carrier will swing roll 301 from contact

with roll 299 into contact with a roll 308 (Fig. 5) on a shaft 309.

From roll 308 ink is transferred to roll 310 on shaft 311, and from roll 310 to roll 312 on shaft 313. From roll 312 ink is transferred by form rolls 314 to the plate cylinder 113. Motion is transmitted from gear 132 on plate cylinder 113 through said gear 264 rotatable on said shaft 265 (Figs. 5, 28), to a gear 317 on roll 312 and from roll 312 through gears 318 and 319 to rolls 308 and 310. Shaft 265 is rotatably supported in frame members 40 and 41. These frame members also carry additional rolls 320, 321 and 322 which assist in effecting uniform distribution of the ink.

Said roll 320 is supported at its front and rear ends by axial projections from the rolls, such as the ends of a shaft 324 resting in open-top recesses in brackets 323 fixed to the frame members 40a and 41a. With this arrangement said roll 320 is urged by gravity against the upper form roll 314.

Said roll 321 is supported by rolls 308 and 312 in the space between the upper parts of said rolls, and is urged against said rolls 308 and 312 by means of slides 326 guided on two pins 327 and urged downwardly by springs 328 attached at their upper ends to said slides 326 and at their other ends to fixed points. Roll 322 has a shaft 329 with ends resting in open slots in pivoted brackets 330 urged inwardly by springs 331 into engagement with the lower form roll 314.

Said form rolls 314 are fixed on shafts 335 which project into open parts of the frame members 40 and 41. At their outer ends said shafts 335 are provided with non-friction bearings such as ball bearings 336 having cylindrical outer casings (Figs. 28, 29, 30). Said form rolls 314 rest against said roll 312 (Fig. 5) and are controlled for movement toward and from each other by levers 337. Such movements involve separation of the form rolls 314 from the plate roll which stops feed of ink to the plate roll or cylinder and movement in the opposite direction to start the feed of ink to the plate cylinder 113.

Said levers 337 (Fig. 36) are mounted on pivots 338 and at the ends toward the plate cylinder or roll 113, each lever is provided with an outwardly-facing recess 339 having a flat bottom 340 and an inclined forward edge 341. A ball bearing 336 is mounted in said recess and is yieldably held in said recess by a finger 342 with one end pivoted in a slot 343 in a lug 344 projecting from the outer edge of the lever. The forward ends of said arms are provided at their inner sides with thin plates 345 to engage the sides of the ball bearing units 336. A helical spring 346 connects each finger 342 with a pin 347 fixed in a stationary member midway between said fingers 342. The arms of levers 337 remote from form rolls 314 are engaged at their outer faces by set screws 348 in stationary parts or posts 349 to enable proper adjustment of the form rollers 314 with reference to the plate cylinder or roll 113.

The shaft 265 (Fig. 39) which is mounted in frame members 40 and 41 is provided with cams 350 between inward projections 351 of levers 337. These cams 350 have parallel sides and arcuate ends (Fig. 29). Also shaft 265 is provided with cams 352 to actuate bellcranks 260 by engagement with downwardly extending arms 263 and separate roll 250 from said plate cylinder 113 thereby shutting off the supply of water thereto. As best seen in Fig. 29, each cam 352 has a low portion on the right of the shaft and extending about two thirds of the way around the shaft. Fixed on said shaft 265 is an indexing disk 353 (Fig. 36) having an arcuate edge with three places for different settings of the shaft 265 at positions (1) where no cam is effective Fig. 29, (2) when cams 350 engage the projections 351 of levers 337 (Fig. 26) and (3) Fig. 27 with the cams 350 still holding said levers 337 apart and the cams 352 holding the levers 260 in

11

position to hold said roll 250 away from the plate cylinder.

Said disk 353 (Fig. 26) has projections 354 and 355 at the right and left ends of the arcuate edge and a notch 356 at the middle of said arcuate edge. A spring pressed detent pin 357 projects from a casing 358 fixed on the frame. As illustrated in Fig. 3, the cams 350 and 352 are ineffective when the right hand projection 354 engages detent pin 357 and a handle or arm 359 fixed on shaft 265 is positioned accordingly.

When the handle 359 is turned counter-clockwise to its middle position with detent pin 357 engaging said notch 356 (Fig. 26), cams 350 have just separated levers 337 to the full extent thereby separating rolls 314 to a substantial extent from the plate cylinder 113 and the cams 352 are in position to lift said roll 250 and separate it from plate cylinder 113. Further movement of arm or handle 359 to its left hand position (Fig. 27) will not affect the position of the form rolls 314 due to the arcuate ends of said cams 350, but the high part of cam 352 will operate said levers 260 to separate roll 250 from the plate cylinder 113 thus interrupting the feed of water to the plate cylinder 113.

With the parts in the position shown in Fig. 26, no ink will be supplied to the plate cylinder 113. With the parts in the positions shown in Fig. 27, the supply of both water and ink to the plate cylinder will be broken.

The throw of the ratchet may be regulated by a ratchet wheel shield in the form of a disk 360 (Figs. 32, 33) mounted on shaft 298 at one side of ratchet wheel 296. Said disk 360 has a low edge portion which is idle at all times and a high portion 361 which acts on the pin 297a to hold pawl 294 out of engagement with the teeth of ratchet wheel 296. Said disk 360 may be turned to different positions by means of a handle or arm 362. The shield or disk 360 may be held in adjusted positions by means of a spring-pressed detent pin 363 having a tapered end adapted to fit into the spaces between detent teeth 364.

The pawl 294 operating the ink roll 299 may also be rendered ineffective by means of a lever 365 on a pivot 366 below the ratchet wheel 296. The left end 367 of said lever (Fig. 33) has an outer or lower edge of convex arcuate outline which when the left end of the lever is swung downwardly by upward movement of the arm 368, will engage pin 297a and hold the pawl 294 out of engagement with said ratchet wheel 296. As shown in Fig. 32 the left end of lever 365 lies between said ratchet wheel 296 and said shield 360.

Referring to Figs. 1, 26, 27 and 33 it will be seen that lever arm 368 is provided with a pin 369 for engagement with and operation by a member in the general form of a sector 370 having a handle 371 near the left end of the curved edge. The apex at the lowermost point of the sector is connected by means including a pivot 373 to the upper end of a link 374. The connection between said sector 370 and said link 374 also includes a pin 375 extending from the link through a circular opening 376 in the sector at the other end of its curved edge from said handle and connected by a tension spring 377 with the opposite radial edge of the sector. Said spring 377 urges sector 370 in a clockwise direction so that the left side of opening 376 engages pin 375.

Under certain conditions to be brought out hereinafter, said link 374 will be moved longitudinally in an upward direction. The sector 370 will then lift pin 369 and swing lever 365 to throw pawl 294 out of action. This corresponds to a setting of other parts. It is sometimes desirable to restore the inking unit to operative condition without changing the condition of other parts of the apparatus. To do this, all that is necessary is to grasp handle 371 and swing it to the left so that sector 370 will no longer support pin 369 which will slip down to the right of the sector (Fig. 3). The link 374 is

12

guided from the frame member by means to be described hereinafter. It will be evident that merely placing the inking unit in place on the main frame will establish an operative relation between pin 369 and sector 370 on link 374, and removal of the inking unit will destroy such operative relations.

System involving eccentric adjustment of the blanket and impression cylinder

10 The stop or gage 61 brings each sheet 50 to rest at a position properly related to the position of the depression on blanket cylinder 112. Thereafter the follower 69 rides upon the high part of cam 67, stop 61 is raised and the sheet is advanced over impression cylinder 66 and below blanket cylinder 112.

A feeler finger 380 (Fig. 5) is secured on a transverse shaft 381 journalled in members 40 and 41 and extending over a slot 382 in plate or platform 57. In normal operation said finger is supported by a sheet 50 when the latter engages stop 61. Said shaft 381 extends through frame member 40 and there, is fixed in a lever 382a, with an upwardly extending arm 384 carrying a pin 383 through which the feeler finger 380 may be shifted, and a downwardly extending arm which is connected by a pivot 385 with a link 386 extending rearwardly with reference to the sheet feed direction.

The rear end of said link 386 is connected by a pivot 387 to the lower end of a swinging arm 388 of which the upper end is mounted on a pivot 389 (Fig. 3). The lower end of said arm 388 carries a pair of parallel guide members 390 on opposite sides of a pin 391 projecting from a member or pawl 392 freely mounted on a pivot 393 carried by the upper end of an actuating bellcrank lever 394 mounted on a pivot 395. At its lower end said lever 394 carries a follower 396 engaging a cam 397 which swings said lever 394 counterclockwise. The return movements may be effected by any suitable means such as a spring 398 (Fig. 4).

Although only one feeler finger 380 is shown, it may be desirable to use more than one to distribute the pressure on a sheet beneath the same.

A bent lever 399 is supported by a pivot 400 at the upper end of a generally vertical arm and the other arm being substantially perpendicular to the vertical arm and extending to the left (Fig. 4) where at its outer end it is connected by a pivot 401 to the rear end of a reciprocating operator or pusher 402. Said pusher is formed at the end remote from pivot 401 with a central extension 403 and shoulders 404 at opposite sides thereof.

Said lever 399 is operated by a cam 405 fixed on shaft 144 and engaging a follower 406 on one end of a lever 407 connected at an intermediate point with lever 399 by a pivot 408 at the bend of said lever 399. A spring 409 connecting a pin on the upright arm of lever 399 with a pin on the left arm of lever 407 urges a pin 410 against the horizontal arm of lever 399 to hold said follower 406 against cam 405. Said lever 407 is also provided with a pin 411 next to follower 406.

A spring 412 urges lever 399 in a direction to hold follower 406 against cam 405. The lever 399 is swung back and forth and reciprocates pusher 402 to rock a lever or rocker 413 about pivot 414 from its Fig. 4 position to its dot-and-dash line position (Fig. 23), or vice versa. The manner of mounting follower 406 on lever 399 whereby it has operable connection only when the cam 405 rotates counterclockwise prevents operation of lever 399 if shaft 144 is turned in a clockwise direction, for example in manual operation by hand wheel 150.

When the rocker 413 is in its upright position (Fig. 4) its upper end supports a lever 415 with its left end mounted on a pivot 416 and its right end connected by a pivot 417 with the lower end of link 374 which is guided at a higher point by a pin 418 extending through a slot 419 in the link and fixed to the frame member 40. With the rocker 413 in this position the link 374

through sector 370 at its top holds the arm 368 of lever 365 in raised position thus preventing operation of the ratchet drive for the inking roll of the ink fountain and stopping the supply of ink.

A link 420 connects a pivot 421 on the upper part of the rocker with a pivot 422 on an arm 423 connected to shaft 175 on which blanket cylinder 112 rotates. Said arm 423 is held on shaft 175 by a toothed sector or gear segment 424 which is fixed on the end of shaft 175 by means including a screw 425. A worm 426 mounted on arm 423 engages gear segment 424 and may be used to effect relative adjustment therebetween. After an adjustment of this kind is made, it may be maintained by means of a screw 427 extending through an arcuate slot 428 in gear segment 424 and screwed into arm 423. Said ball bearings 178 are held in place by means of an annular plate 429 secured to member 177 by means of screws 430 (Fig. 25).

As illustrated in Fig. 4 the eccentric mounting of shaft 175 has been turned to shift blanket cylinder 112 away from impression cylinder 66. Spring 431 acts to hold the parts in the position shown and for this purpose is connected at one end to pivot 422 on arm 423 and at the other end to a pin fixed to said frame member 40. With the rocker 413 in upright position its upper part is in engagement with a set screw 432 which serves as an adjustable abutment to limit counterclockwise movement.

When there is no sheet to be engaged by the feeler finger 380, the pawl 392 on lever 394 will strike a shoulder 433 on the top of a lever 434 and swing it about its pivot 435. A link 436 is connected at one end to lever 434 at a point beneath the pivot 435 and at the other end by a pivot 437 to a member 438 on pivot 400. The pull on the link 436 swings member 438 clockwise and through a pivot 439 thereon lifts a link 440 which lifts the operating end of pusher 402 by means of a flexible connection therewith.

A pin 441 fixed on pusher 402 extends through an opening in the link 440 and is suspended in said opening by tension springs 442 extending in opposite direction from said pin 441 to pins 443 fixed to said link. This provides necessary flexibility required in shifting the rocker. After the pusher has been raised in this way, forward movement thereof would cause the upper shoulder 404 to strike an upper pin 444 on the rocker and shift it from a position inclined to the right and engaging a set screw 45, to the Fig. 4 position. Then so long as the feeler finger 380 is not held in raised position the pawl 392 will continue to strike shoulder 433 on lever 434 and lift pusher 402 so that it would have no effect on rocker 413. Lever 434 is returned to its normal position by the weight of the pusher and the connecting parts.

In each rearward movement of pawl 392 the forward end thereof rides upon a fixed member or pin 446 to lift the feeler finger 380. This lifting of the pawl lifts the feeler finger 380 and if the finger is maintained in raised position during forward movement of pawl 392 the pusher 402 would not be lifted and the rocker would be shifted to its dot-and-dash position of Fig. 23 and the blanket cylinder 112 would again come into contact with the plate cylinder and the impression cylinder. It will be evident that lifting of the feeler finger 380 may be effected manually by moving pin or handle 383.

Means for controlling the separation of the impression cylinder from the plate cylinder

A very important feature of the invention resides in the means for controlling the movement of the impression cylinder 66 to and from the blanket cylinder 112. As already pointed out said cylinder 66 is mounted on shaft 182 by means of ball bearings 183 carried by the shaft and enclosed in openings in the heads 66a of said impression cylinder, keyed to the front end of shaft 182 at the outer side of said ball bearings is an eccentric sleeve or journal member 185 which is rotatably

mounted at the front of the machine in a cylindrical bearing member or sleeve 186 fixed in frame member 40. The outer end of said bearing member 186 projects beyond the outer face of frame member 40 and serves as a pivot for an annular plate 450.

At the outer face of said annular plate 450 (Figs. 4, 22), a member or block 451 is rotatably mounted on shaft 182 and is spaced from frame member 40 by an annular ridge or projection at its inner face. Said member 451 and annular plate 450 may be held against relative movement by a locking pawl 452 on a pivot 453 fixed to plate 450 and having at its left end a tooth 454 adapted to enter a notch or recess 455 in the block or member 451.

Preferably the right wall (Fig. 22) of said notch is substantially radial with respect to the axis of shaft 182 and the left wall is parallel to the first wall and somewhat higher to prevent overriding. Said pivot 453 is substantially the same distance from the axis of shaft

20 182 as the outer part of notch 455 so that the pawl 452 in a locking position will exert a direct pull on said pivot 453. Said pawl 452 is urged toward its locking position by means of a spring 456 (Fig. 22) connected at one end to the end of the pawl tail 457 which is substantially 25 perpendicular to the body of the pawl, and at the other end to a pin 458 on said plate 450. A pin 459 on said pawl engages an offset portion 460 of a lever 461 (Fig. 19) mounted on pivot 453 of lever 434. Said lever 461 is utilized to block feeler finger 380.

30 Secured to said block 451 on a flat portion of its upper part is a bracket 462 extending to the left (Fig. 22) and having a high flat portion 463 with an opening therein receiving a screw threaded rod 464. Above said flat portion 463 is a milled nut 465 to raise or lower said rod 464 thereby either increasing or decreasing the tension of a helical spring 466 connected at its lower end to a pin 467 on a flat arm 468 having at its inner end an opening shaped to receive a portion of shaft 182 having opposite flats 469. Said arm 468 is held in place on shaft 182 by a nut 470 (Fig. 20) and a device such as a screw 471 has a shank 472 passing through an arcuate slot 473 in arm 468, and a head 474. Usually arm 468 and block 451 may be spread apart or brought together under the tension of spring 466, in accordance with the thickness of material passed therethrough. When material of only one thickness is to be used, screw 471 may be tightened, to lock block 451 and arm 468 together.

The shaft 182 and the eccentric sleeves 185 which are fixed together are so positioned that the downward pressure of the impression roll tends to stretch tension spring 50 466 and move impression roll 66 downwardly thereby separating it from blanket roll 112. The yielding resistance to downward movement of impression roll 66 may be adjusted by turning nut 465 to vary the tension 55 of spring 466. This yielding support for the impression cylinder enables the machine to adjust itself automatically for different thicknesses of material passed through the machine.

60 Adjustment of the angular positions of the shaft 182 and the eccentric sleeve 185 may be effected by turning annular plate 450 to a desired position and clamping it to frame member 40, by means of bolts or screws 476 passing through arcuate slots 475 in plate 450 and fixed in frame member 40. Obviously only one device 475 may be used.

65 Mounted on said shaft 182 (Fig. 20) at the outer side of flat arm 468 is a sleeve 480 held on the reduced end of the shaft by a cap 481 which in turn is held in place by a screw 482 extending through the base of the cup and screwed into the end of the shaft. A handle or lever 483 is secured to said sleeve 480 to turn the same on shafts 182. Said sleeve is provided at its inner end with an arm 484 (Fig. 22) which has an arcuate slot 485 receiving a pin 486 projecting from the member 451 and limiting the extent of relative movement therebetween.

As shown on Fig. 4, arm 484 has a straight upper edge engaging said pin 459 on pawl 452 and a depression 487 (Fig. 4) at the right end of said straight upper edge to receive and hold said pin 459 when arm 484 is turned counter-clockwise to its final position.

As pin 459 moves in a clockwise direction about pivot 453, it engages offset portion 460 of lever 461 and swings lever 461 to engage pin 383 and rock shaft 381 far enough to block downward movement of said feeler finger 380 at a level just above that which would be assumed by the upper surface of a sheet 50 if present. As brought out hereinafter this feature is very important.

Secured at its upper end to arm 484 is a detent member 490 provided at its lower end with a rearward projection such as a pin 491 engaging the upper surface of the left end of a second detent member 492 pivoted at 493 on plate 450 at a point to the right of shaft 182. Said detent member 492 is held against said pin 491 by a generally horizontal spring 493 connecting the left end of said detent member to a pin 495 projecting from plate 450. Just to the right of pin 491 when handle 483 is in its normal upright position (Figs. 4 and 23), detent member 492 is provided at its upper edge with a notch 496 having side edges substantially perpendicular to the upper edge of said member 492 and with the distance between said side edges greater than the thickness of said pin. A link 497 is pivoted at one end to said member 492 and has at its other end a slot 498 receiving a pin 499 projecting from the lower end of said lever 434.

In order to assure more rapid action of certain parts, provision has been made of additional spring connections. The return spring 398 which is connected to the lower arm of lever 399 is connected at its other end to plate or arm 484 to assure rapid return of the handle 483 and associated parts from their positions in Figs. 19 and 22 to their positions in Figs. 4 and 23.

Also, instead of depending merely on gravity to return parts to their normal positions the right arm 368 of lever 365 is urged downwardly by a spring 500 (Figs. 1 and 38) connected at its upper end to said arm 368 and at the other end to frame member 40a, handle 461 (Fig. 4) is connected by a spring 501 to pin 70a on frame member 40, and member 451 is urged in a counter-clockwise direction by a spring 502 connected at its left end to a member 503 projecting downwardly from the lowest part of block 451 and at its right end to a pin 504 projecting from plate 450.

Additional discussion of certain features of the machine

In order to print or make impressions on successive sheets 50, the sheets must be presented at the impression cylinder at regular intervals, preferably by any suitable feeding means or feeder. Herein there is no specific disclosure of a complete feeder. However, certain parts of such a feeder are disclosed.

The sheets 50 about to be fed to the impression cylinder 66 are one by one gaged and properly aligned by means of a stop or gage 61 comprising a flat upper part 63 resting on the top of a rock shaft 64 and centrally pivoted thereon and having at its forward edge downwardly extending fingers or teeth 59 to engage the front edge of a sheet to be fed to the impression cylinder 66. It should be understood that the flat top 63 is not necessarily continuous but may have cutouts which will not impair the operation. One end of said pivoted stop is urged forwardly by a spring and the other end pressed forwardly by suitable means such as a conical nut for adjustment purposes.

The lowermost positions of the lower ends of teeth 59 are readily fixed by adjusting the arm 70 around shaft 64. Arm 70 turns around the shaft and is adjustably connected with an arm fixed on the shaft. The adjustment between the arms is effected by screw means acting against a spring. This adjustability avoids the necessity for extreme precision of manufacture which might soon be lost.

The forward edge of each sheet is gripped by spring fingers 65 mounted on said impression cylinder 66 and carried over said cylinder 66 and beneath the blanket cylinder 112 which prints or makes the impressions.

5 The sheet is then passed between cylinder 66 and a rotary delivery device 115 where the fingers 65 release the sheet and the spring fingers 114 on the disks 123 of device 115 take over and carry it around to a point of discharge where the sheet is released by said fingers 114 and delivered to a chute 139. The disks 123 have bevelled edges and therefore have slight contact with the printed face of a sheet.

The cam shaft 144 has the same rate of rotation as the shafts 170, 175 and 182 of the plate, blanket, and impression cylinders respectively, and rotates in the same direction as the shaft 182 of the impression cylinder 66.

A cam 397 operates a lever 394 counterclockwise at each rotation of shaft 144. This movement has no effect unless the pawl 392 at its upper end engages shoulder 433 on the upper end of lever 434 which through link 436 controls pusher 402 to throw blanket cylinder 112 out of operative relation with the plate and impression cylinders. In ordinary operation the rocker 413 is in its dotted line position (Fig. 23) with its upper end engaging set screw 445. The link 420 has then been forced up by toggle action of the rocker and link against the resistance of spring 431, and the blanket cylinder 112 is in operative position and the link 374 through which the ink supply is cut off is in its depressed position and ineffective.

30 If there is no sheet 50 positioned at the stop 61, the feeler finger 380 drops and frees pawl 392 from its control. In its forward movement pawl 392 strikes shoulder 433 on lever 434 and operates the latter. Lever 434 when moved in this direction acts through link 436, rocking member 438 and link 440 to raise the pusher 402 into position for engagement of its upper shoulder 404 with the upper pin 444 on the rocker 413. Advance of the pusher 402 by the cam 405 and intermediate connection will then shift rocker 413 to its Fig. 4 position with the link 420 urged downwardly by spring. The blanket cylinder 112 will thus be withdrawn from the plate cylinder 113 and the impression cylinder 66 when the cover 93 (Fig. 9) of the opening 90 of the impression cylinder and the opening 180 of the blanket cylinder come together.

45 As long as there is no sheet 50 in position to support the feeler finger 380 the lever 434 will be actuated for each rotation of the cylinder 66 and there will be no shifting of rocker 413 and the blanket cylinder will remain in its "out" position. If the feeler finger 380 be held up in any way, lever 434 will not be operated by pawl 392 and the pusher will strike the lower pin 444 and swing rocker 413 to its Fig. 4 position through shifting link 420 upwardly to restore the blanket cylinder 112 to its operative position. The link 420 is thrust upwardly by toggle action of link 420 and rocker 413 which carries upper pin 421 past center.

50 In putting the machine into operation when there is insufficient ink on the plate cylinder, the blanket cylinder may be thrown out of position and ink and water supplied to the plate cylinder 113 until there is sufficient ink thereon. In order to supply ink under these conditions it would be necessary to swing sector 370 to the left about its pivot 373 on link 374 thereby freeing pin 369 on lever 365 which will then be swung with the aid of spring 500 to free pawl 294 (Fig. 3). Ink in tray or fountain 300 will then be fed by roll 299 to ductor roll 301 and passed by the intermediate rolls to the form rolls 314 which apply it to the plate cylinder 113.

55 The machine may also be operated to hold the impression cylinder 66 separated from the blanket cylinder 112 while the blanket cylinder is in contact with the plate cylinder thus enabling proper preliminary inking of the plate cylinder. The handle 483 is swung to the left from its vertical position and the straight but rearwardly in-

clined upper edge of arm 484 engages pin 459 on pawl 452 and swings the pawl to lift locking tooth 454 out of notch 455 in block 451 to release the block from plate 450 to which pawl pivot 453 is secured.

The block 451 then turns counterclockwise partly because of the weight of shaft 182 and the parts carried thereby and partly because of the action of tension spring 502. This movement is checked however by engagement of pin 486 projecting from block 451, with the left end of slot 485 in arm 484 (Fig. 22). Further movement of arm 484 brings pawl 452 to its Fig. 22 position with pin 459 in a depression 487 and arm 484 locked against any further advance.

In the clockwise movement of pawl 452, pin 459 swings lever 461 clockwise to engage pin 383 on the upper arm of lever 382a and block downward movement of feeler finger 380 through the slot in plate 57. When pin 491 on the first detent member reaches notch 496, the detent member 492 swings upwardly and draws link 497 to the left so that the end of slot 498 engages pin 499 on the lower arm of lever 394.

The blocking of the downward movement of feeler finger 380 prevented the lowering of pawl 392 to strike shoulder 433 and prevented operation of lever 434. Consequently the pusher 402 was not lifted and with the lever 483 in its leftward position, the blanket cylinder will be in operative relation with the plate cylinder and the impression cylinder will be withdrawn from the blanket cylinder thus enabling the blanket cylinder to be properly inked.

When the lever 483 is released it will move until pin 491 engages the left end of notch 496 in detent member 492 and the movement of handle 483 will be checked. This short movement will however release lever 461 and permit the feeler finger to drop. This will be followed by engagement of pawl 392 with shoulder 433 and swinging of lever 434. The resulting pull of link 497 will swing member 492 to release pin 491. Spring 398 will then return lever 483 to its upright position and lock block 451 by means of pawl 452.

Another feature of the invention relates to the arrangement for cutting off the supply of water from the plate cylinder 113 by lifting the water molleton 250 which normally rests on the top of said plate cylinder. In a well known manner water is taken up by a roll 223 in the water pan or fountain and transferred to a ductor roll 240 which is swung back and forth on arms 242 to transfer water from roll 223 to oscillating or reciprocating roll 247. From roll 247 water is transferred to molleton roll 250 and then to cylinder 113. As shown in detail in Figs. 5 and 34, an elongated gear 252 is driven directly from gear 132 on the plate cylinder and gear 252 on shaft 243 drives a narrower gear 251 on a shaft 248 which carries said roll 247. Shaft 248 is oscillated by device 251a (Fig. 2) and is mounted in arms 248a urged by springs 249 to press roll 247 against roll 250. The yielding pressure of roll 247 on roll 250 is necessary to permit roll 250 to be lifted from plate roller 113 (Figs. 5 and 34).

In order to drive the gears in the removable ink supply unit from gear 132, it is necessary to place in a projecting part of main frame members 40 and 41 a shaft 265 carrying a gear 264 meshing with a gear 317 in the removable ink supply unit. The gear 312 is on the same shaft 309 as roll 312 which supplies ink to said form rolls 314 which are mounted on shafts 335 carrying ball bearing units 336 (Figs. 29 and 36) which are held in the projecting ends of levers 337 on pivots 338 of frame members 40a and 41a.

The inner ends of levers 337 are held against spreading to keep the rolls 314 separated to pass above and below shaft 265 and engage plate cylinder 113. The fingers 342 and springs 346 keep rolls 314 in engagement with roll 312 of the inking unit. The inking unit (Fig. 36) may be placed in position with the frame members 40a and

41a resting on frame members 40 and 41 and secured thereto as hereinbefore described, the gear 312 in mesh with gear 264, the pin 369 on lever 365 over sector 370 on link 374 guided on frame member 40 (Fig. 33), and link 27 connected to pawl carrier 271 (Fig. 38). The inking units may be changed to change the ink or for cleaning purposes.

It should be noted that when follower 396 is on the low dwell part of cam 397, pawl 392 is in its raised position supported by pin 446. Guide members 390 are also raised and through link 386 and other connections hold feeler finger 380 in raised position. In its forward movement, pawl 392 after it rides off pin 446 is dependent for its position upon feeler finger 380, and during the return movement the feeler finger 380 is raised by pawl 392 as the pawl rides up on pin 446 and the feeler finger is held in raised position until the pawl moves forward. Also pusher 402 will be held in advanced position either up or down while in engagement with the upper pin 444 or the lower pin 444 respectively and the follower 406 is on the high dwell portion of cam 405. Furthermore the body of the pusher 402 is of such breadth that the forward end of the pusher will to a great extent be guided between the pin 444 in a substantial part of its path.

It should be understood that various changes can be made and that various features can be used without others, without departing from the true scope and spirit of the invention.

I claim:

1. In apparatus of the character specified for printing on successive sheets, the combination of an impression cylinder, a blanket cylinder to make an impression for each revolution thereof on sheet material passing between said cylinders, a plate cylinder for forming on said blanket cylinder a pattern to be impressed on said material passing over said impression cylinder, means for driving said cylinders in unison, a feeler, a single eccentric means mounting the blanket cylinder for movement of the latter away from both the impression cylinder and the plate cylinder, and means controlled by said feeler to turn the single eccentric means and move said blanket cylinder away from the other cylinders at the completion of an impression when absence of a sheet for a following impression is indicated by said feeler and to return said blanket cylinder when presence of a sheet for a following impression is indicated by the feeler, said means controlled by said feeler comprising a rocker, a fixed pivot on which said rocker is mounted at an intermediate point, pins in said rocker at opposite sides of said fixed pivot, a pusher having a narrow central part extending between said pins and a broader body providing shoulders to engage either of said pins and preventing edgewise movement away from the pin engaged, means to determine the path of said pusher, and means to actuate said pusher including a pusher lever pivotally mounted at one end and pivotally connected with the pusher at the other end, a cam operated lever pivotally mounted on the pusher lever for rotation in one direction only, and a pusher cam rotating at the same speed as the cylinders and engaging the cam operated lever to operate the pusher solely in one direction of rotation.

2. In apparatus of the character specified for printing on successive sheets, the combination of an impression cylinder, a blanket cylinder to make an impression for each revolution thereof on sheet material passing between said cylinders, a plate cylinder for forming on said blanket cylinder a pattern to be impressed on said material passing over said impression cylinder, means for driving said cylinders in unison, a single eccentric means mounting the blanket cylinder for movement of the latter away from both the impression cylinder and the plate cylinder, a rocker connected with the eccentric means, a fixed pivot mounting the rocker at an intermediate point, a pin on said rocker on each side of said fixed pivot, a pusher having a narrow central part extending

between said pins and a broader body providing a shoulder on each side to engage one of said pins, a feeler for the sheets, means operated by the feeler means for determining the path of the pusher comprising a cam shaft rotated at the same rate as said cylinders, a cam on said cam shaft for controlling said pusher to determine the action on the rocker, and means to actuate the pusher comprising a second cam on said cam shaft having an operative extent of at least 180° extent to hold the pusher in operated position.

3. In apparatus of the character specified for printing on successive sheets, the combination of claim 1 wherein said means for determining the path of the pusher comprises a cam shaft rotated at the same rate as said cylinders, a cam on said cam shaft for controlling said pusher to determine the action on the rocker, and said pusher being mounted on said cam shaft.

4. In a machine of the character specified, the combination of a blanket cylinder, an impression cylinder, a feeler to test the presence or absence of a sheet, a lever pivoted at an intermediate point, a cam acting on the lower end of said lever and having a low dwell and a high portion to advance the upper end of the lever, and free the feeler to move downwardly to detect the presence or absence of paper, a pawl pivoted on the upper end of said lever, means to raise the pawl at the end of its rearward movement thereof, a connection between said pawl and said feeler whereby lifting of said pawl in its rearward movement lifts the feeler and forward movement of the pawl releases the feeler which then controls the forward movement of said pawl, and a second pivoted lever having a shoulder in its upper end to be struck by the pawl if operated by said second lever to control the operation of other parts of the machine.

5. In a machine of the character specified, the combination of a blanket cylinder, an impression cylinder, a shaft about which said impression cylinder rotates, cylindrical journal members in which said shaft is fixed eccentrically, cylindrical bearing members for said journal members fixed in the front and rear frame members, a block fixed to said journal member at one side of the machine, an annular plate fixed to the adjacent frame member between the same and said block, means for locking said block to said annular plate, an arm fixed on said shaft to prevent relative rotation and spring means connecting said arm to said block to permit movement of said impression cylinder from said blanket cylinder to adjust itself to the thickness of the material passed therebetween.

6. In a machine of the character specified, the combination according to claim 5 wherein release of said locking means for said block permits further separation of said impression cylinder from said blanket cylinder, and provision is made of means to limit the downward movement of said arm.

7. In a machine of the character specified, the combination according to claim 5 wherein said locking means for said block comprises a pawl, a pivot therefor projecting from said annular plate and having at one end a locking tooth substantially perpendicular to said pawl, a spring to act on said pawl to urge said tooth toward said block which is provided with a notch to receive said tooth, an arm, and means actuated by said arm to unlock said pawl to permit movement of said block and then to lock said block against further movement.

8. In a machine of the character specified the combination of a plate cylinder, a blanket cylinder, an impression cylinder, gears on said cylinders always in mesh, a cam shaft rotatable at the same rate as said cylinders, a cam having a short raised dwell portion and a long low dwell portion, an upright timing and actuating lever mounted on a pivot at an intermediate point, means urging the lower end of said lever against the side of the cam toward the entrance end of the machine, a pawl pivoted to the top of said lever, means for raising said pawl at

the rear end of its movement, a feeler finger on a rock shaft to test the presence or absence of a sheet, connections between said pawl and said feeler whereby the pawl will lift the feeler at the rear end of its movement, an up-

5 right arm on said rock shaft, means to cause downward shifting of said impression cylinder and to block said upright arm to prevent downward movement of said feeler finger, means for locking said impression cylinder in lowered position but having a lost motion enabling the 10 release of said arm and actuation by said pawl to release said locking means.

9. In a machine of the character specified, the combination of an impression cylinder, a shaft about which said cylinder rotates, cylindrical journal members in

15 which said shaft is fixed in eccentric position, fixed bearing for said journal members, a block mounted to turn on said shaft and having a latching notch, a pawl on a fixed pivot with a tooth to enter said notch and a pin projecting laterally adjacent said tooth, an arm fixed on said

20 shaft, a spring connecting said arm to said block and permitting movement for adjustment to the thickness of material receiving printing thereon, a second arm rotatable on said shaft, and a handle connected to said second arm, said second arm having a slot receiving a pin projecting

25 from said block and having an upper edge with a notch at its outer end, counterclockwise movement of said handle causing said upper edge of the second arm to act on said laterally extending pin and withdrawing said tooth from said notch and forcing said pin into the notch at

30 the upper edge of the second arm thus locking the handle against further movement.

10. In a machine of the character specified, the combination according to claim 9 in combination with a downward extension of said second arm with a rearwardly ex-

35 tending pin, a pivoted latching member supported by a spring and having a part normally engaged and held down by said pin and a long notch which when the pin moves thereover allows upward movement of the latch and a slight advance of the pin, and means rendered effective during return of the pin to the end of the notch to shift said latching member to ineffective position.

11. In a machine of the character specified, the combination according to claim 10 wherein there is a spring urging said handle to return to normal position so that 45 unless the handle is held manually in its operated position it will return immediately to its normal position.

12. In a machine of the character specified, the combination of a blanket cylinder, an impression cylinder, shafts for said cylinders, means urging said impression

50 cylinder into operative relation with said blanket cylinder but yieldable to compensate for different thickness of material, means for releasing said impression cylinder from said urging means and limiting the separating movement thereof, a lever loosely mounted on the impression cylinder shaft, means operable by said lever to actuate said

55 releasing and limiting means, a part moving back and forth for each revolution of said impression cylinder, a pawl pivoted to said part, means for lifting said pawl at the rear end of its movement, a feeler mounted on a

60 transverse shaft, a connection between said feeler and said pawl whereby the pawl lifts said feeler at the rear end of its travel and in the forward movement of said pawl moves up and down with said feeler, said connection including an arm projecting upwardly from the

65 feeler shaft, a lever mounted on a fixed pivot, and means for operating said last mentioned lever to engage the upwardly projecting arm on the feeler shaft to block downward movement of said feeler.

13. In a machine of the character specified, the combination of a blanket cylinder, an impression cylinder, shafts on which said cylinders rotate, means urging said impression cylinder into operative relation with said

70 blanket cylinder but yieldable to compensate for different thickness of material, a handle loosely mounted on the impression cylinder shaft, a feeler to determine pres-

ence or absence of material, means operated by said handle to release said impression cylinder from said urging means, lock said cylinder against further withdrawal and finally block said feeler against downward movement, a downward extension of said handle, a spring-controlled **5** detent member pivoted at one side of said impression cylinder shaft and extending beneath and engaging the end of said downward extension of said handle, said detent member having a notch to receive the lower end of said extension when the handle is moved counterclockwise, a substantially vertical lever pivoted centrally and having a shoulder at its upper end, a link pivoted to said detent member and having at its other end a slot receiving a pin on said lever, release of said detent member drawing said link forwardly to bring the end of the slot up to the pin, a second lever operated at each rotation of the shaft and having a feeler controlled pawl at its upper end to engage said shoulder on the first mentioned lever when said feeler is down, said handle in its return movement first releasing the feeler which causes actuation of the first **10** 20

mentioned lever to act through said link to release said handle for further movement.

14. In a machine of the character specified, the combination according to claim 13 wherein there is a spring to return said handle.
